WHEEL CENTER UNIT

Daniel C. Chadwick, 316 S. San Gabriel Blvd.,
North Hollywood, Calif. 91776

Filed Jan. 16, 1970, Ser. No. 20,956

Term of patent 14 years

Int. Cl. D12—16

U.S. Cl. D14—30

FIG. 1 is a front elevational view of a wheel center unit showing my new design.

FIG. 2 is a cross-sectional view as taken on the line 2—2 of FIG. 1.

FIG. 3 is a cross-sectional view as taken on the line 3—3 of FIG. 1.

FIG. 4 is a rear elevational view drawn to a smaller scale.

I claim:

The ornamental design for a wheel center unit, as shown.
